UNITED STATES PATENT OFFICE

JOHN W. KAYE, OF LULING, TEXAS

CLOSURE CAP SECURING ATTACHMENT FOR CONTAINERS

Application filed May 31, 1932. Serial No. 614,560.

The invention relates to containers and the like and particularly to an attachment for preventing the loss of the removable cap for the container, and has for its principal object 5 the provision of an attachment of the class referred to that is hingedly secured relatively to the container and provided with means to adjustably secure the cap thereto so as to permit rotation and removal and replacement 10 of the cap.

A further object of the invention is the provision of a cap securing device including an arm hingedly mounted on the container and provided with an elongated slot to receive the stem of a stud mounted on the cap so as to permit rotation and removal and replacement of the cap relatively to the container and to prevent loss of the cap and misplacing it.

20 A further object of the invention is the provision of an attachment of the type stated including an arm hingedly mounted on the container and provided with an elongated opening to receive the stem of a stud secured 25 to the cap, the end of the arm being also provided with an opening extending inwardly from the outer end of the arm and communicating with the elongated opening so as to permit removal and replacement of the arm 30 relatively to the stem of the stud.

A further object of the invention is the provision of an attachment of the type stated in which the arm is formed of a single strand 35 of wire bent to provide an elongated opening for the stem of the stud on the cap, the wire being so bent as to provide an opening through the end of the arm communicating with the elongated opening therein.

40 The invention will be described in detail hereinafter and will be found illustrated in the accompanying drawings, in which

Figure 1 is a top plan view of a sheet metal container showing my attachment applied thereto and connected with a screw cap closure for the dispensing nozzle,

Figure 2 is an enlarged fragmentary sectional view taken on a plane substantially as shown by the line 2—2 in Figure 1,

Figure 3 is a sectional detail on a plane indicated by the line 3—3 of Figure 2,

Figure 4 is a view similar to Figure 3 showing a slight modification,

Figure 5 is a side view in elevation of the upper fragment of the collapsible container showing another modification,

Figure 6 is a top plan view on an enlarged scale of the form shown in Figure 5,

Figure 7 is a fragmentary sectional view on a plane indicated by the line 7—7 of Figure 6,

Figure 8 is a fragmentary plan view of a further modification showing the application of the device for use in connection with the valve stems of the inner tubes of automobile tires, and the attachment formed of strands of wire,

Figure 9 is a view taken at right angles to Figure 8 partly broken away and in section,

Figure 10 is a sectional detail on a plane indicated by the line 10—10 of Figure 8,

Figure 11 is a sectional view on a plane indicated by the line 11—11 of Figure 9,

Figure 12 is a fragmentary view in elevation of a further modification showing the application of the invention to a bottle,

Figure 13 is a view taken at right angles to that of Figure 12,

Figure 14 is a top plan view of the device as disclosed in Figures 12 and 13,

Figure 15 is a plan view of a further modification, and

Figure 16 and 17 are side and end views of the modification shown in Figure 15.

In the drawings similar reference characters are used to designate corresponding parts throughout the several views.

In Figures 1, 2 and 3 is shown one form of the attachment for preventing loss of a closure cap as applied to a sheet metal container 20 and having a screw cap 21 mounted on a threaded nozzle 22. The cap 21 has

a headed stud 23 secured thereto in any suitable manner, and 24 is an arm hingedly secured as shown at 25 to a supporting member 26 provided with an angular foot piece 27 5 secured as shown at 28 to the top of the container adjacent to the nozzle 22. The arm 24 is provided with an elongated opening 29 to receive the shank of the stud 23 and also with a V-shaped opening 30 that extends 10 from the free end of the arm 24 inwardly and is in communication with the elongated opening 29 by means of a relatively narrow communicating opening 31.

In Figure 4 is shown a modification in 15 which the arm is designated 24' and hingedly secured as shown at 25' to a supporting member 26' having an angular extension 27' that is secured by soldering as shown at 28' to the top of the container 20, the arm being provided with an elongated opening 29', and the end of the arm 24' is provided with a narrow opening 31' connecting the outer end of the arm with the elongated opening 29'.

It will be apparent that the elongated 25 openings 29 and 29' permit rotation and upward and downward movement relatively to the container of the screw cap 21, and when the screw cap is removed from the nozzle 22 it will be retained against misplacement. 30 The openings 30, 31 and 31' permit of bending the arms on the two sides of the openings to permit insertion of the stem of the stud 23 into the elongated opening, the arms 24 and 24' being made of sheet metal 35 for this purpose.

In Figures 5, 6, and 7 is shown a further modification in which the arm 24^a is pivotally mounted as shown at 25^a on a supporting member 26^a having an inturned angular extension 27^a secured as shown at 28^a to the top of a collapsible container 20^a adapted to hold dental paste, shaving cream, and other like commodities and provided with a threaded nozzle 22^a on which is a threaded cap 21^a having a stud that is shown as a bolt 23^a secured thereto. The arm 24^a is provided with an elongated opening 29^a engaging the stem of the stud 23^a, said opening being closed as shown.

50 In Figures 8, 9, 10 and 11 is shown a modification of the attachment and also applied to a valve cap as used on the valve stems of inner tubes of automobile tires, the valve stem being designated 40 and the screw cap 41, and provided with an integral stud 42. The attachment for mounting the screw cap in the figures referred to is made of a strand of wire bent intermediate of its ends to form the arm 43, the wire being separated to provide an opening 44 to receive the stud 42, and the extremities of the wire brought together and bent downwardly as shown at 45 and provided with loops 46 to receive a loop 47 of a securing member 48 also formed of a single 65 strand of wire bent intermediate of its ends

to provide the loop, the member 48 being soldered or otherwise secured as shown at 49 to a sleeve 50 enclosing the valve stem 40.

In Figures 12, 13, and 14 is shown a further modification of the attachment as applied to a bottle or like container 51 having a screw cap 52 secured thereto with a stud 53 thereon, the attaching arm being designated 54 and also made of a single strand of wire and to provide an elongated opening 55 to receive the stud 53, the arm 54 having a downturned portion 56 provided with loops 57 that are engaged by means of a loop 58 on a securing member 59 that is secured around the neck of the bottle.

In Figures 15, 16 and 17 another modification of the attaching member is shown unapplied to a container, the arm in this form of attachment being made of a single strand of wire also bent intermediate of its ends, and the bent portion again bent inwardly between the opposite strands of the wire to provide an opening 60 in the arm 61 to receive the stem of a stud, and providing a narrow opening 62 through which the stem may be inserted into the elongated opening 60 by spreading the arms 63 formed by the bent wire as heretofore described. The extremities of the wire are also provided with loops 64 to receive a loop 65 on a securing member 66 that may be secured in any suitable manner to a container, such for instance as shown in Figures 8 to 14, inclusive.

What is claimed is:—

1. In combination with a container, and a removable cap therefor, a headed stud on said cap, an arm hingedly mounted on the container and provided with an elongated opening to receive the stud, and the arm also provided with an opening extending from an edge thereof and communicating with the elongated opening for insertion of the stud therein.

2. In combination with a container, and a removable cap therefor, a headed stud on said cap, an arm hingedly mounted on the container and provided with an elongated opening to receive the stud, and the arm also provided with an opening extending from its free end and communicating with the elongated opening for insertion of the stud therein.

3. In combination with a container, and a removable cap therefor, a headed stud on said cap, an arm hingedly mounted on the container and provided with an elongated opening to receive the stud, and the arm also provided with a V-shaped opening extending from its free end and communicating with the elongated opening for insertion of the stud therein.

4. In combination with a container, and a removable cap therefor, a headed stud on said cap, an arm hingedly mounted on the container, said arm being formed of a single

strand of wire bent intermediate of its ends, the bent portion being bent inwardly of the adjacent portions of the wire to provide an elongated opening to receive the stud, said 5 opening being reduced in width at the free end of the arm for insertion of the stud in the elongated opening, the free ends of the wire provided with loops, and a retaining member secured to the container and provided 10 with a loop engaging the first mentioned loops.

In testimony whereof I affix my signature.
JOHN W. KAYE.
